POCKET SUPPLEMENT HOLDER AND ATTACHMENT THEREFOR

Samuel B. Kraus, Chicago, Ill.

Application August 19, 1953, Serial No. 375,202

4 Claims. (Cl. 281—17)

The invention relates generally to supplement holders for books such as law books, such holders permitting the attachment to the books of pocket supplements by means of which the contents of the books can be periodically brought up to date.

In connection with the foregoing, an object of the invention is to provide an improved supplement holder and an attachment for the holder which will permit the holder to be affixed to the cover of a book.

Another and more specific object of the invention is to provide an improved supplement holder for receiving a pocket supplement and to additionally provide in connection therewith a novel attachment member for the holder in the form of an envelope and which has telescoping relation with a cover of the holder and with a cover of the book for releasably attaching the holder to the book.

Another object of the invention resides in the provision of a pocket supplement holder and an attachment member therefor by means of which the supplement holder can be affixed to the front cover of a book on the outside thereof. As a result, the book is not disfigured nor is the back or the binding thereof broken as is often the case when a pocket supplement is fitted within the book.

A still further object is to provide a new and improved holder and attachment member therefor for affixing a pocket supplement to the outside of a book, which will be of simple construction, embodying very few parts, and which will have universal application, being adaptable to all kinds of books.

Another object of the invention resides in the provision of a pocket supplement holder and attachment member for affixing the holder to a cover of a book, the said combination permitting release of the pocket supplement at any time although the supplement is at all times adequately protected and available for reference.

With these and various other objects in view, the invention may consist of certain novel features of construction and operation, as will be more fully described and particularly pointed out in the specification, drawings and claims appended hereto.

In the drawings which illustrate an embodiment of the device and wherein like reference characters are used to designate like parts—

Figure 1 is a perspective view showing a book having a pocket supplement affixed thereto by the holder and attachment member of the invention;

Figure 2 is a transverse sectional view taken along line 2—2 of Figure 1;

Figure 3 is a perspective view of the supplement holder of the invention showing the inside of the covers of the holder for illustrating the structural details thereof;

Figure 4 is a perspective view of a conventional pocket supplement; and

Figure 5 is a perspective view of the attachment member of the invention which is employed to releasably retain the holder to a cover of a book.

Referring more particularly to the drawings, the com-

2

bination comprising the invention consists of a supplement holder generally designated by numeral 10, Figure 3, and an attachment member 12, best shown in Figure 5. The holder is designed for receiving a conventional pocket supplement such as indicated by numeral 14, Figure 4, and said holder, with the pocket supplement inserted therein, is releasably attached or affixed to a cover of a book by the attachment member 12 which has telescoping relation, preferably with the rear cover of the holder and with the front cover of the book.

For illustrating the invention a permanent volume or book 15 of conventional construction has been selected, said book consisting of the pages 16, front cover 17, and rear cover 18. The said front and rear covers are joined by the conventional back 19 forming the rear of the book and to which the pages 16 are secured by the binding 20, all in a manner well understood in the art. Publishers of law books, in particular, and also publishers of reference books, digests and the like, provide pocket supplements from time to time in order to render the contents of the respective books current and up to date. It has heretofore been customary to affix the pocket supplement to the inside of the rear cover of the book, which practice is not entirely satisfactory since the addition of the supplement tends to enlarge the book whereby possible damage to the binding and general disfiguration of the book may occur. The combination of the present invention has effectively solved the existing problem in connection with pocket supplements by providing a holder 10 for the supplement which protects the same by the front and rear covers therefor and which is releasably affixed, preferably to the front cover of the book, by the attachment member 12 in the form of an envelope, all of which will be particularly described in detail as the description proceeds.

The pocket supplement 14, as shown in Figure 4, and which is representative of the supplements such as are provided for the books to which the invention pertains, essentially consists of pages 21 which are stapled and bound to front and rear flaps by means of the binding tape such as 22. For purposes of the present invention it is only necessary that the pocket supplement have a front flap such as 23. Should a rear flap also be provided, as may sometimes be the case, the invention is equally adaptable thereto with no structural change in the parts being required. The pocket supplement is combined with the holder 10 by insertion of the flap 23 in a pocket such as 24, provided by the holder. Said holder essentially consists of a front cover 25, a rear cover 26, and the intermediate backing 27. The holder may be formed of fairly heavy material similar to that comprising the covers of the book, or the holder may be formed of lighter material such as fabric, paper, imitation leather or plastic.

A single sheet may be suitably bent into shape to form the front and rear covers of the holder 10, with the front cover 25 thereof having a portion 28 folded into overlapping relation with the inside surface to form the pocket 24, previously referred to. The folded overlapping flaps 30 are glued or otherwise secured to portion 28 to complete the formation of the pocket. Similar folded, overlapping flaps 31 are provided to complete the formation of the cover. In a like manner the rear cover 26 is formed with the folded, overlapping flaps 32 and which are glued to the inside of said cover. The pocket supplement 14 is placed in the holder and releasably retained in proper relation within the holder by insertion of the flap 23 of the supplement in pocket 24. The position of the parts with the supplement in inserted relation in the holder is illustrated in the perspective views, Figures 1 and 2.

The supplement holder 10 with the pocket supplement

14 affixed thereto has the general appearance of a book but with a reduced number of pages when compared with that of the volume 15. In fact, the two books may have substantially the same external appearance, this constructional feature merely requiring that the supplement holder be made of material similar to or having an external finish like that of the covers of the book 15. Also, it will be understood that the supplement holder will be constructed of a size whereby the covers thereof, namely, 25 and 26, will substantially equal in area the covers of the book to which the holder is to be attached. Although some deviation with respect to the size of the holder covers is possible, the most attractive appearing combination results when the supplement holder and the book are designed to have the same or substantially similar cover dimensions.

The attachment member 12 of Figure 5 essentially consists of an envelope having substantially parallel sides 33 and 34 connected by side edges 35. One of the sides such as 33 may be indented in an arcuate manner such as at 36, although such indentation is optional, and likewise the side edge 35 may be omitted along the back edge 37. However, if the edge is continued around three sides of the envelope a strong and more durable article is provided. Here also the size of the attachment member 12 is somewhat critical since the member is designed to have telescoping relation with a cover of the book and supplement holder respectively. The length and width of the attachment member must be large enough to have telescoping relation with the cover of the book to which the same is to be applied. The thickness of the member, which is determined by the side edges 35, must be sufficient to accommodate two covers, namely, the rear cover 26 of the supplement holder and the front cover 17 of the book.

In assembling the several elements of the present supplement holder, it is preferred that the supplement 14 be first attached to the holder 10 and that the holder be then affixed to the cover of its intended volume by the attachment member 12. With the flap 23 inserted in pocket 24 and the covers 25 and 26 closed on the supplement 14 it will be seen that a companion supplement or book is provided substantially the same in area dimensions as the permanent volume and of pleasing and attractive appearance when combined therewith. The physical association of the companion supplement and the permanent volume is effected by the attachment member 12 which, as shown, has telescoping relation with the front cover 17 of the permanent volume and with the rear cover 26 of the supplement holder.

The invention is not to be limited to or by details of construction of the particular embodiment thereof illustrated by the drawings, as various other forms of the device will of course be apparent to those skilled in the art without departing from the spirit of the invention or the scope of the claims.

What is claimed is:

1. In an article of the character described, the combination with the front cover of a book, of a supplement holder having an attachment pocket, and an attachment member for releasably securing the said holder to the outside of said cover, said attachment member having telescoping relation with the rear cover of the holder and with said front cover of the book.
- 15 2. In an article of manufacture, a pocket supplement holder including a front and a rear cover, a pocket provided on the inside surface of the front cover of the holder, and an attachment member in the form of an envelope for releasably securing the holder to the cover of a book, said attachment member being adapted to have telescoping relation with the rear cover of the holder and with the front cover of said book.
- 20 3. An article of manufacture for releasably attaching a pocket supplement to a book, a holder for the pocket supplement consisting of a unitary article providing a front cover, a rear cover and an inside pocket in associated relation with one of said covers, and an attachment member for the supplement holder for releasably affixing the same to said book, said attachment member comprising an envelope adapted to have telescoping relation with a cover of the holder and with one of the covers of the book.
- 25 4. In a book, of means for attaching a pocket supplement to the exterior of said book, in combination, a supplement holder formed from a strip of material and folded to provide a front cover, a rear cover and an inside pocket in associated relation with the front cover, said pocket being adapted to receive a flap provided by the pocket supplement whereby to affix the supplement to the holder, and an attachment member in the form of an envelope, said attachment member having telescoping relation with the rear cover of the holder and with the front cover of the book to attach the holder to the book.
